UNITED STATES PATENT OFFICE.

THEODORE I. GROVE, OF HARTLAND, MINNESOTA.

JAR-COVER.

No. 918,815.

Specification of Letters Patent.

Patented April 13, 1909.

Application filed June 13, 1908. Serial No. 438,843.

To all whom it may concern:

Be it known that I, THEODORE I. GROVE, a citizen of the United States, residing at Hartland, in the county of Freeborn and State of Minnesota, have invented a new and useful Jar-Cover, of which the following is a specification.

This invention relates to an improvement in jar closures, and is particularly adapted 10 for use on butter jars, although the closure may be applied to various other receptacles.

The object of the present invention is to provide a device of the character described, which is simple in construction, easy of operation 15 and cheap to manufacture.

A further object of the invention is to provide a jar cover or lid having a handle, and means for locking the cover to the jar, which will permit of the jar being carried by means 20 of said handle.

A still further object of the invention is to provide a jar cover having means for readily locking or unlocking the cover to or from the jar.

25 In the drawings:—Figure 1 is a face view of a jar showing the cover with the locking means applied thereto. Fig. 2 is a face view of a jar showing the cover detached therefrom. Fig. 3 is a top plan view of the clamping rim. Fig. 4 is a detail cross sectional view of a portion of the cover.

Similar reference numerals designate corresponding parts in all the figures of the drawings.

35 Referring to the drawings, 1 designates a jar of any style having a bead 1^a and having a cover 2 on which are secured spaced upstanding ears 3 and 3^a respectively, to which the bail 4 of a handle 5 is attached. The 40 cover 2 is provided with a depending flange 6, which is adapted to embrace a ring 7 formed of wire or any other suitable material. At various intervals, a portion of the flange is cut away as shown by the reference 45 numeral 8 to permit of the fastening of the link members 9. These members are preferably formed of flat pieces of metal having their upper ends 9^a bent around to embrace the ring 7. The lower ends 9^b of said members 50 are also bent around to form bearings for an open locking ring 10. The two free ends 10^a and 10^b respectively of this ring are bent to form hooks or bearings for the cam locking member 11. This cam locking member 55 11 is preferably formed of a single piece of wire and is bent to form two loops, one

larger than the other and having converging sides 11^a and 11^b, one of said sides being arranged more at an angle than the other.

It will be evident from the foregoing description that to lock the cover to the jar, it is only necessary to position the cover on the jar, depend the clamping ring 10 below the bead 1^a of the jar 1, turn the cam locking member 11 so that the ends 10^a and 10^b of the ring 10 are arranged within the small loop of said member, and then force the larger loop of the locking member up to the ring 10. Thus the cover 2 is securely locked to the jar. Thus it will be seen that the jar may be carried from place to place by means of the handle 5.

From the foregoing, it is thought that the construction, operation and many advantages of the herein described invention will 75 be apparent to those skilled in the art, without further description, and it will be understood that various changes in the size, shape, proportion, and minor details of construction, may be resorted to without departing 80 from the spirit or sacrificing any of the advantages of the invention.

Having thus fully described my invention, what I claim as new, and desire to secure by Letters Patent, is:—

85 1. The combination with a receptacle having a bead at the upper portion thereof, of a cover provided with a handle, a ring-shaped clamping member arranged to engage the bead of the receptacle, links pivoted to the cover at one end and to the clamping member at the other end, and means for contracting the said member in applying the cover to a receptacle.

90 2. In combination with the cover, spaced links depending from and pivoted to the peripheral edge thereof, a ring-shaped clamping member carried by the lower ends of the links, and means for contracting the said member in applying the cover to a receptacle.

95 3. The combination with a receptacle, of a cover provided with a depending flange having spaced cut-out portions, a ring adapted to be retained by the flange, links pivotally mounted on the ring within the cut-out 100 portions of the flange, a clamping ring carried by said links and provided with hooked ends, and a cam locking member arranged to engage the hooked ends for locking the cover to the receptacle.

105 4. The combination with a receptacle having a bead arranged near the upper portion

thereof, of a cover provided with a depending flange having spaced cut-out portions, a ring carried by said flange, spaced links carried by said ring and arranged within the cut-out portions of the flange, an open-ended ring carried by the links and provided with a bearing at each end, and means for contracting the said member in applying the cover to a receptacle.

- 10 5. The combination with a receptacle, of a cover provided with a depending flange having spaced cut-out portions, a ring adapted to be retained by the flange, links pivotally mounted on the ring within the cut-out portion of the flange, a clamping ring carried by said links and provided with hooked ends, and a cam-locking member formed of a single piece of metal bent to form a small and

a large loop having their connecting sides converging, said small loop engaging within the hooked ends of the clamping ring and adapted to clamp said ring to the receptacle. 20

6. In combination with the cover having a ring-shaped clamping member, and a cam-locking member connecting the two ends of the said clamping member, said cam locking member being formed with a large and a small loop and an intermediate contracted portion. 25

In testimony, that I claim the foregoing as 30 my own, I have hereto affixed my signature in the presence of two witnesses.

THEODORE I. GROVE.
